PATTERSON FARMER, OF DETROIT, MICHIGAN

REGULATABLE BELLows MECHANISM OF REFRIGERATION SYSTEMS

Application filed August 28, 1929. Serial No. 388,905.

This invention relates to a sealing and travel control regulating means for use in the chamber appurtenant the controlling bellows in an artificial refrigeration system, and has for its object an improved organization of parts adapted to effectively seal from access of the outside atmosphere those parts of the interior of the shell within which the controlling bellows is positioned.

To a degree, effectiveness of the shell closure against the entrance of atmospheric moisture may be attained by properly tightened gasket joints, or by daubing of the threadings and the slip fit in the terminal cap with heavy grease, but in case of even a slight movement of one part, as of the cap, relatively to the bellows-enclosing chamber, it has been my experience that while the exclusion of atmospheric moisture may seem to be effectively attained thus for a time, sooner or later a leaking or seepage, of atmospheric moisture occurs in apparatus thus assembled, which is highly destructive of its efficiency. To the correction of this, and as well, to the effecting of definite adjustability of the possible expansion and contraction of the bellows, I have devised the improved organization of parts forming the subject of this invention, which deals only with the solution of this problem of sealing, though for clearness of illustration of its place and function, relatively to other parts of the refrigeration system as a whole, I have of course illustrated other adjacent parts, which are admittedly old, and with whose details this application is not concerned.

In the drawings:

Figure 1 is a sectional elevational view, showing my improved construction in position relatively to the bellows shell and the connected parts.

Figure 2 is a perspective of my improved construction with part of the shell broken away to show the relation of the contained parts of the mechanism thereto.

Figure 3 is an end view of the mechanism partly in section through the line 3-3 of Figure 1.

Figure 4 is a fragmentary sectional elevational view of a slightly modified form of shell closure cap and connected parts from the showing of the corresponding part at the right-hand end of Figure 1.

Figure 5 is a view of a corrugated disc diaphragm, which may under some circumstances be used alternatively for and in place of the supplemental bellows diaphragm illustrated.

At A on the left-hand side of Figure 1 is shown fragmentarily the end of a needle-valve-actuating arm, variant types of which are now quite familiar, for the control of the refrigerant flow through a part of the mechanism of a refrigerating system. The end of this needle-valve-actuating arm engages against the end of, or in a recess or indentation in, the wall of the diaphragm B, which is housed within the shell C, and against the diaphragm B extends the valve pin D, the other end of which is enclosed within the cross-sectionally V-shaped shell E. The right-hand end of this latter, as viewed in Figure 1, broadens out into the housing F, for enclosure of the controlling bellows G, against whose adjacent end the right-hand end of the valve pin D engages. The end of the housing F is adjustably closed by the engagement thereover of the centrally apertured cap H, through the center of which a slip fit opening K permits the passage of the tube J, which opens into the interior of the diaphragm bellows G.

The weak point of the presently known system, as regards both adjustability of the cap and as regards the slip fit thereof with respect to the tube J which carries the active thermostatic element into the interior of the controlling bellows G, is the fact that though for a time adequate doping or smearing of the slip fit and of the threads of the cap may

adequately serve to protect the interior of the shell F and its connected parts from the access of atmospheric moisture, sooner or later this sealing, effective though it may be at the outset, becomes impaired to a degree that admits moisture to the interior of the shell F and its connected parts, thus forming a freezing coating upon the outside convolutions of the bellows diaphragm G, upon the exterior of the valve pin D, and proceeding further, upon the internal convolutions of the bellows diaphragm B, thus deleteriously affecting the accuracy, and indeed the freedom, of movement of these parts.

15 To obviate this objection, I propose to isolate them from possible access of atmospheric dampness, while permitting the desired degree of adjustability of the cap H relatively to the shell F and to the controlling bellows G, and my preferred form of effecting this comprises a supplemental or protective diaphragm M, one terminal edge of which is soldered or otherwise suitably secured to the opposite end of the diaphragm bellows G from that which engages the end of the valve pin D. The opposite end of this supplemental bellows M is carried over and hermetically sealed against the end of the shell F, thus shutting off any possible communication between the space N in the interior of the shell F, which surrounds the bellows diaphragm G, and the space S which is bounded by the adjacent end of the diaphragm G, the wall of the supplemental bellows M, and the inner face of the cap H.

This cap H is provided with a slip fit K which permits the passage therethrough of the tube J, which opens into the interior of the diaphragm bellows G, and which outwardly extends to a suitable storage chamber T. The cap H has a rather deep marginal skirting H' which threadedly engages the correspondingly threaded portion of the end of the shell F so that an adequate degree of adjustability of the former relatively to the latter may be had without danger of its structural detachment therefrom. From the center of the cap H a tube or chimney P extends inwardly, surrounding the slip fit J and the pipe K so as to adjustably engage against the adjacent end of the bellows diaphragm G, thus restricting its possible expansive movement in that direction.

Since the back-and-forth movement of the valve pin D, in the direction and to the degree called for by the conditions prevailing with respect to this part of the mechanism, it will be in the system at any time, is the basic function, it is obvious that the accurate effectuation of this must depend upon the proper cooperative movement of the diaphragm B against one end and of the controlling diaphragm bellows G upon the other end of the valve stem D. The expansive action of the bellows diaphragm G, due to its interior being a part

of the space wherein the active thermostatic element is confined, of course effects the movement of the valve stem to the left, and its contractive movement permits the valve stem to be forced to the right by the action of the diaphragm B, due to the action against it of the needle-valve-actuating arm A, or some equivalently functioning member or force, or a combination of them. All of this expansive and contractive movement and the resultant movement of the valve stem D takes place, however, within the space N or its connected and communicating spaces about the valve pin D, or within the chamber to the right of the diaphragm B, without possibility of access of atmospheric dampness, such of which as may enter through the slip fit K or through the threadings appurtenant the skirting of the cap H, merely finding its way harmlessly within the space S enclosed within the supplemental diaphragm M, into which the chimney or tube P fixedly, though adjustably, projects, thus limiting the possible degree of movement of the adjacent end of the diaphragm bellows G according to the selected adjustment of the cap H.

As an alternative to the described threading of the marginal skirting of the end closure cap H for effecting the desired positioning of the tubular stop P relatively to the end of the diaphragm bellows G, I have shown in Figure 4 a modified construction of this part, wherein the threaded engagement of the end of the shell or housing F by the cap H is immaterial except for assembly or structural purposes, the chimney or tube P' here shown being externally threaded and the bore in the cap H' through which it passes being similarly threaded so that by retraction or projection of this relatively to the cap, the shell and the diaphragm end the desired position of its end as a stop for the adjacent end of the bellows diaphragm G to strike against may be attained.

It should also be understood, as within the scope of this disclosure that in place of the quite elongatable supplemental bellows M, the outer end or edge of which is shown in Figure 1 as sealingly carried over the edge or end of the housing F, I may use some such alternative as the corrugated disc diaphragm V, which I have illustrated in Figure 5, the outer edge of which, instead of being carried over the end of the shell or housing F, is sealingly set into the wall thereof at a point almost if not quite in the same transverse plane as the end wall of the diaphragm bellows G to which its other edge is soldered.

What I claim is:

1. In a refrigeration system, in combination with a housing having a valve pin adapted to slide through one end thereof, a bellows diaphragm positioned in the housing and having a tubular connection extending from the housing to an externally located contain-

- er for the active thermostatic element, a cap adjustably positioned upon that end of said housing through which said tubular connection extends, said cap having a slip fit over 5 said tubular connection and an interiorly projecting portion adapted to engage against the adjacent end of said bellows diaphragm according to the adjusted position of the cap with respect to said housing, and means 10 for sealingly isolating that portion of the interior of said housing occupied by said bellows diaphragm from the remaining portion thereof, comprising a bellows member sealingly connected at one end with the adjacent end of said bellows diaphragm and at 15 the other end with the wall of the housing.
2. In a refrigeration system, in combination with a valve pin adapted to be actuated in one direction by and according to the 20 variant pressure conditions prevailing in a relatively remote part of the system, an active thermostatic element comprising a housing into an end of which one end of said valve pin movably projects, a bellows diaphragm 25 located within said housing and a connected externally located supply container, a supplementary bellows element sealingly connected at one of its terminal edges with the other side of said bellows diaphragm from 30 that engaged by said valve pin and at the other of its terminal edges with the wall of said housing, and a cap operatively and adjustably connected with the initially open end of the housing, said cap having a slip fit 35 engagement over the connection between the bellows diaphragm and the external supply container and being provided with an inwardly projecting portion adapted to engage against the adjacent end of the bellows dia- 40 phragm to limit the thermostatically induced expansion thereof in the direction of the cap.
3. In a refrigeration system, a housing adapted for connection with piping of the system, a temperature responsive member 45 and a bellows diaphragm member the latter located in said housing and adapted to expand and contract in response to external thermal variations, a centrally apertured cap closing one end of said housing and through which 50 the recited connection with said bellows dia- phragm member passes, said cap having an inwardly extending projection adapted to adjustably engage against the adjacent end of said bellows diaphragm to limit the ex- 55 pansive movement thereof toward said cap, and a protective bellows member connected at one end with said bellows diaphragm and at the other end with the wall of said housing, whereby that portion of the interior of 60 the housing wherein said bellows diaphragm is located is sealed against access of atmospheric dampness regardless of the adjusted position of the cap relatively thereto and to the shell of said housing.
- 65 4. The combination, with a terminally apertured shell constituting a connected unit of a refrigeration system, of a pair of terminally engaging bellows members located therewithin, one being adapted to be expandingly and contractingly acted upon by transmitted thermal variations from another part of the system communicated thereto through one of said apertures in the shell, and the other of said bellows members serving, co-operatively with that end wall of the shell 70 surrounding the outlet aperture therein and to which the otherwise open end of said bellows is sealingly connected, in isolating the space thus enclosed from communication with the remainder of the space within the shell, and means located adjacent the otherwise open end of said last-named bellows member and adapted to act against a cross wall portion of said first-named bellows member whereby possible expansive movement of the latter toward said means in response to transmitted thermal variations may be adjustably regulated.
5. In a refrigeration system, means for effecting a regulatable variance in the degree 90 of potential response of a bellows mechanism to transmitted variations in temperature, comprising, in combination therewith and with a terminally apertured enclosing shell, a second bellows member sealingly connected with one end of said first-named bellows member and with the wall of said shell adjacent the outlet aperture therein, whereby communication between the space thus enclosed and the remaining portion of the interior of the shell is precluded, and adjustable end closing means for the shell adapted to be engaged by the adjacent end of the first-named bellows member whereby 95 the degree and direction of potential response by the latter to transmitted thermal variations communicated to it from the other points in the system is made regulatable.
6. The combination, in a refrigeration system, of an integrated shell member operative- 100 ly connected therewith, a bellows member located within said shell member in position of potential elongative and compressive response to transmitted thermal variations, means for isolating the remainder of the interior of said shell from that portion thereof immediately surrounding said bellows member, comprising a second bellows member terminally engaging the adjacent end of 105 the first-named bellows member, and appropriate portion of the wall of the shell, and an adjustable stop member positioned within the space located at one end of said first-named bellows member, whereby the degree and direction of possible expansive action 110 in the direction thereof may be regulated.
7. In combination with a pair of terminally connected bellows members, a terminally apertured surrounding shell wherein said bellows members are located and with an 115 120 125 130

adjacent wall portion whereof one end of one of said bellows members is connected, thereby isolating the space thus enclosed from the remainder of the interior portion of said shell, and means operable against the end of the bellows member first above mentioned whereby the degree of possible response by it to transmitted thermal variations from a point exterior of said shell may be regulably varied.

10 In testimony whereof I sign this specification.
